UNITED STATES PATENT OFFICE.

IRA F. PECK, OF WARWICK, RHODE ISLAND, ASSIGNOR TO THE NATIONAL BUTTON COMPANY, OF PROVIDENCE, RHODE ISLAND, A CORPORATION OF RHODE ISLAND.

EYELETING-MACHINE.

SPECIFICATION forming part of Letters Patent No. 689,222, dated December 17, 1901.

Application filed May 31, 1901. Serial No. 62,547. (No model.)

To all whom it may concern:

Be it known that I, IRA F. PECK, a citizen of the United States, residing at Warwick, in the county of Kent, State of Rhode Island, have invented a certain new and useful Improvement in Eyeletting-Machines, of which the following is a specification, reference being had therein to the accompanying drawings.

10 The present invention relates to an eyeletting-machine, the object of the invention in general being to obtain an improved machine in which the machine shall punch the stock or material in which eyelets are to be set and feed and set the eyelets automatically.

15 Certain features of the invention are designed to be employed in machines for setting a single eyelet at a time; but in its more complete embodiment the invention comprises a 20 machine in which a number of eyelets may be set at one operation. When it is designed to set a single eyelet at a time, the machine is provided with a single punch and a corresponding pair of eyelet-setting members or 25 setting-tools. When it is designed to set a number of eyelets at one operation, a machine embodying the invention is provided with a gang of punching-tools properly arranged to 30 punch a number of holes at a single operation in the material in such position relative to the latter and to each other as may be desired and with coöperating gangs of setting-tools for setting the eyelets in the previously-punched holes. The punching-tools may 35 advantageously be arranged to coöperate in the punching operation with one gang of the setting-tools or sets, each of which latter acts as a combined punching and setting anvil, and the said punching-tools are arranged in a 40 manner to support and guide the eyelets in the setting operation.

45 Figure 1 of the drawings is an elevation of the front portion of a machine embodying the invention. Fig. 2 is a view thereof, partly in section, on the vertical plane indicated by the dotted line 2-2 in Fig. 1. Fig. 3 is a side view more especially designed to illustrate the application to the machine of a form of eyelet-feeding mechanism which may be employed. Figs. 4, 5, and 6 are sectional de-

tail views designed to illustrate the working of the parts in punching a hole in the material and setting an eyelet. Fig. 7 shows in front elevation one of the detachable blocks or mountings carrying the gang of punches 55 and the gang of setting-tools with which the punches are more immediately associated in the machine. Fig. 8 shows in end elevation the block of Fig. 7 and the parts which are carried thereby.

60

Having reference to the drawings, 1 designates the fixed framework of the machine, and 2 is an operating-shaft mounted in suitable bearings 3 at the front of the said fixed framework, the said shaft being provided with 65 suitable means of communicating movement of rotation thereto, a simple band-pulley 4 being represented for convenience of illustration. Any approved and suitable driving arrangements may be employed in practice.

70

The punches 5 are tubular and are in screw-threaded connection with the punch-carriers 6, the latter being open at one side, as at 61, for the egress of the pieces of material which are punched out. The punch-carriers 6 are 75 mounted in chambers in a block 7, having slots 8, with which the openings 61 register, thereby permitting of the escape of the said pieces of material. The punches 5 work in central holes through the upper sets 9, the 80 latter being in screw-threaded connection with the block 7 and each thereof having the annular setting-shoulder 91 around the hole in which the hollow punch works. The lower sets are shown at 10, they having each the annular setting-shoulder 100 and the central 85 punching table or surface 101, against which the punch is arranged to cut. The lower sets 10 constitute combined punching and setting anvils. They are carried by a block 11, which is mounted on the bed 1^a of the machine.

90 At 12 are shown raceways, which may be of usual character and construction, they extending at their lower ends into close proximity to the punching and setting devices, and at 13 is shown a supply-hopper, which in practice will be provided with means of any approved character for delivering eyelets to the raceways 12. The raceways, the means 95

100

of supplying eyelets thereto, and the means of operating the raceways may in practice be of any suitable and approved construction. For the purposes of illustration I have shown 5 the raceways as attached to the hopper and the latter in turn as mounted upon horizontal slide-rods 14, only one of which is shown, although in practice a pair thereof will be used—namely, one at each end of the hopper—the said rods being fitted within guides 142 on the head of the machine and being provided with rolls 141, working against cams 15 on the shaft 2. A spring or springs 161, connected with some portion of the hopper and 15 with some fixed portion of the framework 1, operates to hold the rolls 141 in contact with the faces of the cams 15.

In operation, the sets being separated and the punches being retracted, as in Fig. 4, 20 and the raceways being in their advanced position, holding eyelets *a* in position above the stock or material *b*, resting on the lower sets or anvils 10, the punches 5 first are depressed, causing them first to pass through the said eyelets, so as to pick them off the raceways when the latter are retracted, and then causing said punches by acting against the material *b* to punch the holes in such material for the reception of the eyelets. The 25 punches remain within the said holes, as in Fig. 5, and then the upper sets 9 are caused to descend, forcing the eyelets lengthwise along the said punches, so as to cause the bodies or barrels of the eyelets to enter the 30 said holes, and finally clenching or setting the eyelets against the lower sets or anvils 10, as in Fig. 6.

I have shown in the machine embodying the invention the punch-carriers 6 as operated by a cam 16 on the shaft 2, the descent thereof beginning prior to that of the upper sets 9. The upper sets are operated by means of eccentrics 17 on the shaft 2, straps and connecting-rods 18, and pins or bolts 19, engaging 45 at their inner ends the slide or carriage 71, which last is fitted to move vertically in ways at 20 on the fixed framework of the machine. The block 7 is detachably applied to the slide or carriage 71, being held to the latter by a face- 50 plate 72, which is removably secured in place on said slide or carriage by means of screws 731. On removing the face-plate 72 the block 7 is exposed and may be removed and replaced. This enables a block 7, containing a gang of 55 upper sets and punches spaced apart with relation to one another suitably for performing one variety of work, to be taken out of the machine and replaced by a similar block having corresponding sets and punches differently spaced. The block 11 is similarly 60 removably applied to the bed 1^a. In the illustrated embodiment of the invention it is placed within a vertical hole or opening in the said bed and is supported vertically by 65 means of laterally-projecting flanges 111 at its upper end resting upon the top surface of

the bed-plate. The punches are raised from their depressed positions by means of springs 61, surrounding the punch-bars 6 between the top of the block 7 and heads or collars 62 70 on the said punch-bars. For the purpose of holding the punch-bars from rotation, which would carry the openings 61 thereof out of register with the slots 8 in the block 7, the punch-bars are provided with laterally-projecting pins 63, working in vertical slots 73 in the block 7. The punched-out pieces of material after issuing through the slots 8 in the block 7 pass through similar slots 711 in the slide 71 and thence fall through the space 80 at 1° in the front side of the cross-bar 1^b.

In connection with each under set 10 I employ an adjusting-screw 110 by means of which to regulate the height of the said set.

In the described construction the punches 85 5 are formed separate from the upper sets 9 and are readily removable and replaceable. In consequence in case of any injury to one of the punches it may be taken out of the machine and another one may be substituted 90 therefor, the corresponding upper set being retained in use.

I claim as my invention—

1. An eyeleting-machine comprising, essentially, in combination, an eyelet-set provided at the center thereof with a fixed solid anvil against which the punch acts in cutting, a second eyelet-set having the central hole therethrough, and the hollow punch working within the said central hole, relatively movable with respect to the second eyelet-set and acting against the face of the fixed solid anvil of the set first mentioned, substantially as described.

2. An eyeleting-machine comprising, essentially, in combination, an eyelet-set provided at the center thereof with a fixed solid anvil against which the punch acts in cutting, a second eyelet-set having the central hole therethrough, the hollow punch working 100 within the said central hole, relatively movable with respect to the said second eyelet-set, and acting against the face of the fixed solid anvil of the set first mentioned, a carrier for said punch, and means for separately operating the said carrier and the eyelet-set through which the hollow punch passes, substantially as described.

3. An eyeleting-machine comprising a movable carriage, means for operating the same, 120 a carrier detachably applied to the said carriage, a gang of sets applied to the said carrier, a gang of punches applied to the carrier in connection with the said sets, and means for actuating the said punches independently, substantially as described.

In testimony whereof I affix my signature in presence of two witnesses.

IRA F. PECK.
